STOPPING DEVICE FOR AUTOMOBILE TORPEDOES.

1,044,543.

Specification of Letters Patent. Patented Nov. 19, 1912.

Application filed February 29, 1912. Serial No. 680,657.

To all whom it may concern:

Be it known that I, FRANK M. LEAVITT, a citizen of the United States, residing in Smithtown, in the county of Suffolk and 5 State of New York, have invented certain new and useful Improvements in Stopping Devices for Automobile Torpedoes, of which the following is a specification.

This invention provides means for stopping an automobile torpedo in the event that the steering apparatus should become inoperative. Torpedoes are commonly steered in a sinuous course by a steering mechanism which quickly throws the rudder from 10 hard-a-port to hard-a-starboard and vice versa, the rudder throw occurring normally whenever the torpedo has veered, by a certain prescribed angle, to either side of its set course. The steering mechanism is controlled by a gyroscope and is somewhat sensitive. There is consequently some liability that some derangement may occur whereby the steering mechanism may fail to operate. In such case it would leave the rudder in 15 the position to which it was last thrown, namely, either hard-a-port or hard-a-starboard, as the case might be. The result would be that the torpedo would, in still water, follow an arc of a circle which would 20 carry it far out of its intended course, and in time of war might cause it to explode the ship or boat from which it was launched or one of the friendly fleet, instead of one of the enemy's ships against which it was 25 directed. Such accidents have occurred with automobile torpedoes during practice runs, resulting in the torpedo returning nearly to its starting point and ramming the boat from which it was launched.

30 The present invention aims to prevent such disaster by providing means for stopping the engine in case the steering gear becomes inoperative or operates so tardily as not to reverse the rudder within a predetermined maximum interval of time from 35 the last previous reversal. In a normal operation the rudder will, after the torpedo heads upon its course, be thrown over at intervals approximating one or two seconds.

40 A sufficiently greater interval, say for example, ten seconds, may be selected for giving ample time for the delayed action of the steering mechanism in case the torpedo were to be slued from its course by the 45 action of some disturbing current. If at

the end of this determined interval it has not thrown the rudder the mechanism provided by the present invention then acts to shut off the supply of motive fluid (compressed air) from the engine which drives 60 the torpedo, so that the torpedo is compelled to come to a stop or lose headway before it can have departed to a seriously dangerous angle from its prescribed course.

In its preferred form the invention provides a moving part or traveler to which motion is imparted at a stated rate from any suitable driving means, such, for example, as the propeller shaft. This traveler starts from a determined starting point and travels 65 thence in the operative direction until arrested by a movement imparted from the steering engine. Hence its travel is stopped whenever the steering engine throws the rudder. It then automatically returns to its starting point and recommences its travel. Normally it never finishes its complete course; but in case the steering mechanism ceases to operate or its operation is delayed 70 beyond the prescribed time, the traveler, 75 continuing its progress, reaches the limit of its course, and in so doing operates some device whereby the supply of air or other motive fluid is shut off from the engine.

A simple and preferable means for embodying the invention comprises a rack and pinion, the rack constituting or connected to the moving part which has been called the traveler, and the pinion connected to the propeller shaft or other driving means, 80 whereby it is given continuous rotation, preferably at a substantially uniform speed. When the rack is in mesh with the pinion the latter slowly moves it in the direction 85 which would bring the traveler to the operative end of its course. A connection is made with the steering mechanism whereby at each throw of the rudder the rack and pinion are unmeshed; and a spring is provided for thereupon drawing the rack back 90 to its starting point. When the steering mechanism comprises an engine or so-called servomotor, the connection for throwing the rack out of gear may be conveniently made 95 with a cross-head or some other moving part of this engine. The means for shutting off the air from the engine may comprise a valve which, at starting, is unseated, being held so during the run by a detent; and the 100 traveler may be adapted, upon reaching the 105 110

end of its travel, to withdraw such detent and thereby permit said valve to close.

To enable my invention to be clearly understood, I have shown in Figure 1, a diagrammatic representation of a torpedo, the view being in general a vertical, longitudinal mid-section and illustrating on a reduced scale and in diagrammatic manner, the application of the present invention to a known type of torpedo. Fig. 2 is an elevation partly in section, showing the stopping mechanism and its connections on a larger scale, the parts being in the starting position of the traveler. Fig. 3 is a similar view showing part of the mechanism of Fig. 2, the parts being shown at the instant when the steering engine has thrown the rack out of mesh with the pinion and the rack is moving back to its starting point. Fig. 4 is a similar view showing the parts in the position where the rack or traveler has been carried to its final operative position and has just finished opening the valve which will insure the stopping of the engine.

Referring first to Fig. 1, let A designate the hollow shell of the torpedo, B the usual compressed air reservoir, C the engine, here shown as a turbine, D the outer propeller shaft, E, E' the propeller screws, F the vertical rudders for steering in a horizontal plane, and G the steering engine, connected to the tiller by the usual tiller rod G'. Compressed air in the reservoir B is admitted through a pipe or conduit a, which is controlled by a starting valve b, and a reducing valve c, the air under reduced pressure being conducted to the nozzle of the turbine C. The starting valve b is operated in well understood manner from the controlling valve H through a communicating tube d. The usual starting hook e which is thrown over during the act of launching, operates a lever f which throws open the controlling valve H, throwing it to the position shown in Fig. 2, in which position it is held by the passing, under the valve stem g, of a detent h which may consist of a notched rod or slide, as shown, having a spring h' which, when the stem g is lifted, causes the detent to pass under it and hold it lifted. These parts are all either of known construction, or at least form no novel part of the present invention, and may be substituted by any known or suitable equivalents.

J is the traveler, the extreme movement of which serves to withdraw the detent and close the valve H. Although it might have various forms it is here shown as a lever pivoted at any suitable point, its free end being adapted to encounter the detent h. The traveler is drawn back by a spring j against a stop j' and is propelled forward by a rack and pinion, the rack being lettered K and the pinion L. The pinion is driven at suitable speed from any suitable

driving part, as for example, from a worm l on the propeller shaft D. The rack K is hung at one end to the traveler J and its other or free end is connected by a rod k to a lever m having a cam projection m' which coacts with a cam projection p' on the cross-head p of the engine G (or on any other suitable part of the steering apparatus).

In operation the traveler, having been brought to its starting position, its rack K is dropped into mesh with the pinion L, this being the position of the parts shown in Fig. 2. Thereupon the rotation of the pinion L carries with it the rack K and moves the traveler J progressively from the starting position shown in Fig. 2 toward the terminal position shown in Fig. 4. Normally the steering engine will throw the rudder before the traveler has moved far from its starting position. When this occurs the cam p' engages the cam m' and lifts the lever m and rod k, thus throwing the rack K out of engagement with the pinion L. Fig. 3 shows the parts thus lifted by the contact of the two cams. As soon as the rack K is thus unmeshed, the retracting spring j of the traveler draws the parts back to the starting position. As soon as the cam p' has passed the cam m' the rack is dropped back into mesh with the pinion, as shown in Fig. 2. The retraction of the traveler to the starting point should precede this engagement of the rack and pinion. Hence in the normal operation the traveler repeatedly is restored to the starting point and recommences from there its progressive movement, being arrested and restored in the early part of this movement; so that the traveler is executing a succession of slow forward and quick return movements so long as the normal operation of the torpedo continues. If, however, the steering apparatus should fail to throw the rudder for a period longer than that for which the traveler is timed, the engagement of the rack and pinion will carry the traveler to the end of its movement, where, as shown in Fig. 4, it strikes the detent h and displaces it so as to release the stem g and close the valve H. The closing of the controlling valve H in turn operates and closes the main air valve b, thus cutting off the air from the engine. Consequently the torpedo, being deprived of power to drive it, soon comes to rest.

To insure that after the disengagement of the rack and pinion these shall not reengage until the return movement of the traveler to its starting point has been completed, a special detent M is provided, the function of which is on the lifting of the rack K to snap under it and hold it up until the completion of the restoring movement, and thereupon to permit the rack to fall into engagement with the pinion. To accom-

plish this the rack has a pin *q* and the detent *M* is drawn by a spring against a stop *r*. In starting, the pin *q* is behind the detent, as shown in Fig. 2, and, as the rack 5 moves forward, this pin strikes the detent and carries it along. Upon the lifting of the rack the pin *q* moves just above the detent and releases it, whereupon the detent is drawn by its spring under the pin so that 10 it holds up the pin and prevents the dropping back of the rack. The parts retain this position as shown in Fig. 3 during the restoring movement, at the end of which the detent *M*, being stopped by its stop *r*, the 15 pin *q* moves behind it and, on dropping off from the detent the rack falls into reengagement with the pinion.

The mechanism may be greatly modified without departing from the essential features of the invention. It will be understood that while I have shown a rack and pinion for imparting movement to the traveler, any other suitable mechanical driving means may be substituted. What I 25 have called the "traveler" and its operating means, constitute, in fact, a form of timing device and may be substituted by any other suitable timing means. That which is essential to my invention is that 30 the timing means shall so coöperate with the steering mechanism that so long as the latter throws the rudder at the normal intervals of time, or without exceeding a predetermined delay beyond the normal, the 35 timing mechanism shall be rendered impotent to operate the means whereby the torpedo is to be stopped or rendered harmless; but in case of undue delay of the steering operation, the action of the timing mechanism will be completed and it will operate 40 the stopping means and cause the consequent stoppage of the torpedo so as to prevent unintended damage thereby.

The timing mechanism need not measure 45 absolute time, but preferably will measure time proportional to the speed of the engine, that is to say, in proportion to the number of revolutions of the propeller shaft. It is therefore preferable to drive it from the 50 propeller shaft or some other part connected to the engine or turbine.

While the stopping of the engine, and thereby stopping the run of the torpedo, is 55 obviously the best means of rendering the torpedo impotent to do accidental or unintended damage, yet my invention does not negative the substitution of other means of rendering the torpedo impotent or innocuous. Any of the means heretofore used for 60 rendering an unexploded torpedo harmless at the end of its run may be employed. It has long been customary with the Whitehead torpedo to provide means for sinking the torpedo in case it completes its run with- 65 out exploding.

What I claim is:—

1. In a torpedo, means for stopping its normal run to render it harmless in case the steering mechanism becomes inactive, comprising a timing device adapted to effect such stoppage at the end of a determined interval, and means connected with the steering mechanism adapted upon the occurrence of a steering movement within said interval to prevent such stoppage. 75

2. In a torpedo, means for stopping its normal run in case the steering mechanism becomes inactive, comprising a timing device, means connected to the steering mechanism for causing the restoration of the timing device upon a steering movement, and means operated at the end of the period determined by the timing device for actuating such stopping means. 80

3. In a torpedo, a timing device comprising a traveler moving from a starting to a stopping point, means for stopping the normal run of the torpedo operated when such traveler reaches its stopping point, and means operated from the steering mechanism and adapted to stop the movement of the traveler and restore it to its starting point. 85 90

4. In a torpedo, the combination of a cut-off valve for stopping the engine, a timing device moving proportionally to the speed of the engine, and adapted on completing its movement to operate said valve, and means operated by the steering mechanism for disconnecting and restoring said timing device upon each steering movement. 95 100

5. In a torpedo, the combination of means for stopping its normal run to render it harmless, a traveler moving from a fixed starting point to a stopping point, adapted on reaching such stopping point to operate such stopping means, the steering mechanism, and a connection between the same and said travel, whereby on each steering movement the traveler is disconnected and 110 restored to its starting point. 105

6. In a torpedo, the combination of a valve controlling the engine, a detent for holding said valve open, a traveler moving from a fixed starting point and adapted, on completing its movement, to displace said detent and close said valve, means for moving said traveler, steering mechanism, and a connection between the latter and said traveler, adapted upon each steering movement to disconnect and restore the traveler. 115 120

7. In a torpedo, the combination with its engine, controlling valve and steering mechanism, of a timing device comprising a traveler moving from a fixed starting point and adapted on completing its movement to operate said valve to stop the engine, gearing for imparting movement to said traveler from the engine, and a connection from the steering mechanism to said gearing adapted 125 130

to disengage such gearing upon each steering movement, whereby to restore the traveler.

8. In a torpedo, the combination with its engine, controlling valve and steering mechanism of a timing device comprising a rack and pinion, the pinion driven from the engine, the rack movable into and out of mesh with the pinion, a connection from the steering mechanism for throwing it out of mesh upon each steering movement, and means for restoring it to its starting position when so unmched.

9. In a torpedo, the combination with its engine, controlling valve and steering mechanism, of a timing device comprising a rack and pinion, the pinion driven from the en-

gine, the rack movable into and out of mesh with the pinion, a connection from the steering mechanism for throwing it out of mesh 20 upon each steering movement, a detent for holding it out of mesh, retracting means for restoring it to its starting point, and a stop for said detent, whereby on reaching its starting point the rack reengages with its 25 driving pinion to recommence its movement.

In witness whereof, I have hereunto signed my name in the presence of two subscribing witnesses.

FRANK M. LEAVITT.
